LUMINAIRE

Leroy C. Doane, Meriden, Conn., assignor to The
Sight Light Corporation, Essex, Conn., a cor-
poration of Connecticut

Application December 29, 1938, Serial No. 248,172

12 Claims. (Cl. 240—73)

The present invention relates to luminaires, and is more particularly directed toward luminaires for illuminating long narrow areas.

The luminaire contemplated by the present invention is designed to be placed below normal eye level and to concentrate the emitted flux into a long narrow region below the luminaire. It is provided with a light source usually in the form of a lamp bulb, an upwardly acting reflector which intercepts downwardly directed light and reflects it upwardly, and a downwardly acting opaque reflector close to the light source and extending laterally from the source to spread light reflected thereby to illuminate the remote areas. It is also provided with laterally extending screens which depend from the laterally extending portions of the reflector to prevent spread of light laterally of the long narrow area to be illuminated. The construction just referred to is one which completely screens the light source at all normal angles of observation and lays down a generally rectangular pattern of light.

The luminaires contemplated by the present invention are particularly designed for illuminating the papers in office files. These files are generally about four feet high and the luminaire is designed so as to be placed on top of the file and to extend upwardly and outwardly so as to be above the drawers when the drawers are pulled out. Owing to the wide lateral spread of light a single lighting unit will illuminate the contents of files on each side of the one supporting the luminaire.

The invention also contemplates arranging the luminaire so that one can obtain symmetric illumination on opposite sides of the luminaire, or can build up the illumination on one side at the expense of the illumination on the other side.

The accompanying drawings show, for purposes of illustrating the present invention, an embodiment in which the invention may take form, it being understood that the drawings are illustrative of the invention rather than limiting the same.

45 In these drawings:

Figure 1 is a diagrammatic elevational view illustrating the luminaire placed on top of a filing cabinet;

Figure 2 is an enlarged transverse sectional view through the luminaire;

Figure 3 is a top plan view of the luminaire with parts broken away;

Figure 4 is a vertical cross sectional view taken on the line 4—4 of Figure 3;

55 Figure 5 is a fragmentary sectional view at an

enlarged scale taken on the line 5—5 of Figure 4;

Figure 6 is a fragmentary view taken on the same plane as Figure 5 showing an arrangement of parts for securing a modified light distribution;

Figure 7 is a chart indicating light distribution from the luminaire lengthwise of the area being illuminated; and

Figure 8 is a similar chart showing light distribution transversely.

The upper part of a filing cabinet is indicated in the drawings at 10 and the luminaire L rests on top of the filing case. It has a weighted base 11, and a tubular arm 12 through which the wiring is carried. This arm is bent so as to extend obliquely upwardly and forwardly of the filing case as indicated. The arm or tube 12 carries a lamp socket 13, socket cover or husk 14 slotted adjacent its end as indicated at 15, Figure 3.

The socket cover is adapted to telescopically receive a fitter 16 and the parts can be clamped together by a band indicated at 17. The upper end of the fitter 16 supports a cup-shaped reflector 18 of suitable size to permit inserting a lamp bulb 19. The light center O of the lamp bulb is below the upper edge 20 of the reflector 18. The reflector 18 carries four spring elements indicated at 21. These may be made in pairs from a single strip of material as shown in the drawings. These spring elements have holes, such as indicated at 22, Figure 4, and are adapted to releasably support the downwardly acting reflecting elements.

Disposed above the lamp bulb is a downwardly acting sheet-metal reflector 25. This reflector is made out of a single piece of sheet metal bent to substantially the shape shown. The center of the reflector 25 is bent down, as indicated at 26, so as to be close to the lamp bulb. From this point the reflector has two laterally extending portions which extend upwardly and outwardly and then substantially horizontally to the outer portions which are bent down so as to terminate slightly above the level of the top 20 of the lower reflector. The edges of the reflector 25 enter into grooves 27 formed in laterally extending screens 28 and 29. These screens are preferably castings and are designed to have the upper contour conform to the shape of the laterally extending reflectors 25 and with the lower edge slightly below the top of the reflector 18. These screens 28 and 29 have central portions which are curved inwardly toward the lamp bulb along a generally parabolic curve, as indicated at 32. The screens

28 and 29 and the downwardly acting reflector 25, together with the upwardly acting reflector 18 very completely screen off the light source so that it will not be seen at ordinary angles of observation.

- In order to more effectively control the distribution of light laterally of the luminaire the invention contemplates the use of transversely extending screens between the depending screens.
- 10 These transversely extending screens are received in grooves 33 formed in the castings 28 and 29. The screen may, as shown at 34 on the left of Figure 4, extend from the upper reflector 25 all the way down to the bottom of the groove 33, thereby cutting off light from the portion of the reflector 25 to the left of the screen, or a narrower screen may be used, as indicated at 35, on the right hand of Figure 4, which permits some light to escape above its upper edge for control by the right-hand side of the reflector 25, or, as shown in Figure 6, the screen 36 may be much narrower and of just sufficient length to cut off direct observation of the upper part of the lamp bulb from below the lower edge of the reflector 25.
- 25 The castings 28 and 29 are provided with pins 37 adapted to enter the holes 22 in the springs 21 so as to support the structure from the lower reflector and to permit swinging it upwardly as indicated in dot-and-dash lines of Figure 4 to facilitate lamp bulb renewal. Spacers 38 and screens 39 are employed to hold the parts together.

When the luminaire is placed on the filing cabinet, as indicated in the drawings, it will be apparent that the eyes of the worker are completely shielded and the light is not spilled on to the top of the filing cases or in front of the open drawers. The light which strikes the upper reflector 25 will be reflected laterally at wide angles 40 away from nadir, and the quantity of light so emitted will depend upon the portion of light intercepted by the transverse screens used. The light which strikes the side walls of the screens 28 and 29 will be reflected by them into generally 45 the same direction as the light reflected from the upper screen so that there will be a good build up of light at remote points.

Figures 7 and 8 illustrate typical foot candle distribution curves of illumination obtained from 50 a luminaire such as described employing a 100 watt bulb and placed 14" above the working plane. Here the solid line curves 50 and 50a show the distribution lengthwise of the illuminated area and transversely of the illuminated area obtained when both transverse screens are narrow, as indicated at 36 in Figure 6. When two medium length inserts, such as 34, are employed, the distribution is altered to obtain the dotted curves 51, 51a. It will be apparent that this 55 has built up a higher illumination near the luminaire. When the luminaire employs a wide and a narrow insert one obtains a distribution curve which is indicated by the x's in the drawings. Part of this curve coincides with the curve 60 50 and part with the curve 51, the intermediate portion 52 being different. The transverse distribution is indicated at 52a.

When the screen 34 is used on one side there is a redistribution of light, depending upon which 70 form of screen is used on the other side, but its principal function is to avoid the possibility of seeing the bright bulb or bright surfaces of reflector 25 at high angles.

When no transverse screens are used there is 75 a build up of light at remote points, but at the

hazard of exposing a source of excessive brightness.

It is obvious that the invention may be embodied in other forms and constructions within the scope of the claims and I wish it to be understood that the particular form shown is but illustrative. Various modifications and changes being possible, I do not otherwise limit myself in any way with respect thereto except as defined in the claims.

What is claimed is:

1. A luminaire symmetrical on opposite sides of a median vertical plane for illuminating a long narrow region below the luminaire on opposite sides of said median plane, said luminaire comprising an incandescent lamp bulb disposed over said region and having the light source thereof in said median plane and above the base thereof, a hemispherical reflector intercepting downwardly directed light and reflecting it upwardly and outwardly, a downwardly acting opaque reflector placed closely adjacent the upper surface of the bulb and having two diametrically opposite, laterally extending portions which spread the light reflected thereby away from the median plane to illuminate the more remote portions of said region and cut off upwardly directed light, and screens extending laterally from said median plane and depending from the said laterally extending portions of the upper reflector and spaced substantially the diameter of the hemispherical reflector to prevent spread of light laterally of the long narrow area.

2. A luminaire such as claimed in claim 1, having transversely extending reflecting screens between the laterally extending screens and under the upper reflector for screening the upper portion of the light source against observation at angles near the horizontal and reflecting light downwardly.

3. A luminaire such as claimed in claim 1, wherein the screens and upper reflector are detachably supported by the lower reflector.

4. A luminaire such as claimed in claim 1, wherein the laterally extending reflectors have straight line sections in planes parallel with the median plane and the central portions of the vertically extending screens are parabolic and reflecting.

5. A luminaire comprising an incandescent lamp bulb with the light source thereof above the base, a concentric hemispherical reflector under the source, a downwardly acting reflector placed closely adjacent the upper surface of the bulb, the downwardly acting reflector having two narrow diametrically opposite, laterally extending portions to spread the light reflected thereby into two narrow beams of downwardly and outwardly directed light substantially 180° apart, and generally parallel, vertical reflecting screens extending downwardly from the edges of the downwardly acting reflectors to screen regions between the beams and of a contour adjacent the bulb to reflect light into the same general radial directions as the light reflected by the downwardly acting reflectors.

6. A luminaire such as claimed in claim 5, wherein the remote edges of the downwardly acting reflectors are slightly above the level of the top of the hemispherical reflector, and the vertical screens extend down from the side edges of the downwardly acting reflectors to slightly below the level of the top of the hemispherical reflector.

7. A lighting unit for lighting the contents of a row of office filing cases, comprising a base adapted to be placed on top of such a filing case, an arm secured to the base and extending forwardly and upwardly so as to terminate above and in front of the filing case, a lamp socket carried on the end of the arm, a lamp bulb in the socket, a reflecting cup under the lamp bulb, diametrically opposite downwardly acting reflectors above the bulb and extending laterally of the bulb for directing light away from nadir into two beams of downwardly and outwardly directed light substantially 180° apart so as to illuminate the contents of the file drawers of the cases, and substantially vertical generally parallel, reflecting screens depending from the side edges of the downwardly acting reflectors to cut off light normally emitted forwardly and rearwardly and direct it into the same general direction as the direct light and the light reflected by the downwardly acting reflectors and confine the area of intense illumination to a narrow region lengthwise of the front wall of the row of filing cases.

8. A lighting unit comprising an upwardly opening, obliquely disposed lamp socket and lamp bulb, a hemispherical reflecting cup about the bulb, narrow screening reflectors disposed in vertical planes and extending generally parallel with one another from opposite sides of the cup, their lower edges being slightly below the top of the cup and their upper edges being slightly above the top of the bulb, downwardly acting reflectors above the light source and between the upper edges of the screening reflectors, and obliquely disposed screens extending between the vertical screening reflectors upwardly from points below the level of the top of the cup.

9. A luminaire having a light source disposed in an upwardly opening reflecting cup, and a combined reflecting and screening unit detachably supported above the cup and comprising two generally parallel, vertical side screens having inwardly facing grooves adjacent their upper edges, a downwardly acting reflector fitted in the grooves, and tie rods extending between the screens and holding the reflector and screens together. 5

10. A luminaire such as claimed in claim 9, wherein the side screens have other pairs of inwardly facing grooves, and transverse screens are secured in said grooves.

11. A luminaire having a light source disposed in an upwardly opening reflecting cup, and a combined reflecting and screening unit disposed above the cup and comprising two generally parallel, vertical side screens having inwardly facing grooves adjacent their upper edges, a downwardly acting reflector fitted in the grooves, and tie rods extending between the screens and holding the reflector and screens together, and cup-carried pivot members for supporting the said unit. 15

12. A luminaire having a light source disposed in an upwardly opening reflecting cup, and a combined reflecting and screening unit disposed above the cup and comprising two generally parallel, vertical side screens having inwardly facing 20 grooves adjacent their upper edges, a downwardly acting reflector fitted in the grooves, and tie rods extending between the screens and holding the reflector and screens together, and laterally extending springs carried by the cup and detachably secured to the said unit. 30
